(57) **CLAIM**

The ornamental design for a camera strap, as shown and described.

DESCRIPTION

The patent contains at least one drawing executed in color. Copies of this patent with color drawings will be provided by the office upon request and payment of the necessary fee. FIG. 1 is a front view of a camera strap showing our new design;

FIG. 2 is a top plan view thereof, the bottom plan view being a mirror image of FIG. 2; and,

FIG. 3 is an enlarged view showing a portion defined by lines 3-3 in FIG. 1.

The broken lines illustrate portions of the camera strap that form no part of the claimed design. The dash-dotted lines denote the boundary of the claim and form no part of the claimed design.
